MARTIN A. BARBER, OF CLEVELAND, OHIO, ASSIGNOR TO CONSOLIDATED CONNECTOR PATENT CORPORATION, OF WILMINGTON, DELAWARE

HEAD FOR AUTOMATIC TRAIN PIPE CONNECTERS

Application filed June 17, 1929. Serial No. 371,851.

This invention relates to automatic train pipe connectors, and is particularly concerned with the construction of a head having a projection and a ring, which cooperates with a corresponding ring and projection on a coacting head. In connectors of this type, there is a likelihood of the ring being bent if the coacting projection should forcibly strike it while the cars are being coupled on a curve. Furthermore, there is a likelihood of the heads being jammed together in improper locking position, if one head is appreciably lower than another, as the usual bearing lug on the projection is apt to be caught behind the wall of the coacting ring. A further difficulty which has been encountered has been the fact that the connector heads are apt to slip past each other on the ring side if the car couplers should fail to couple under extreme conditions of track curvature.

The principal object of the present invention is to minimize the possibility of failure of the heads to lock in the proper position, and to reinforce the ring construction so as to strengthen the head. A further object of this invention is to facilitate withdrawal of the heads to normal position in the event that the heads should slip past each other on the ring side during the coupling operation under extreme track curvature conditions. My invention, thus aims to increase the operating efficiency of an automatic train pipe connector by strengthening the parts against fracture, and by decreasing the possibility of failure to couple in the proper manner.

Referring now to the drawings, Fig. 1 is a side elevation of a pair of coupled train pipe connectors, embodying my invention; Fig. 2 is a horizontal section taken on an enlarged scale through the pair of coupled connector heads; Fig. 3 is a front elevation of a connector head embodying my invention and Fig. 4 is a section through the head on line 4-4 in Fig. 3.

The automatic train pipe connectors, which I have illustrated are supported from brackets 10, which are arranged to be carried by and to depend from the usual car couplers. Each connector has a head 11 from which a shank 12 extends rearwardly and is con-

nected to the associated bracket by a universal joint indicated in general at 13. A spring 14 surrounds the shank and normally urges the head forwardly of the bracket. Each head is also shown as having a projection 15 and a ring 16, which are intended to cooperate with a corresponding ring and projection on a coacting head. Such projection and ring are mounted on opposite sides of the axis of the projection while ports 17, 18 and 19 are positioned on a vertical line between the head and ring for the air signal, air brake and steam conduits respectively. Bearing lugs 20 and 21 are mounted on the projection and are intended to engage the face 22 of the ring when the heads are coupled.

To expedite and facilitate coupling of the heads in the proper manner, I provide an inclined guideway which extends from the head to the outer part of the ring. Such guideway, in the form illustrated, comprises a web 25, which extends transversely of the head at the forward end of the shank, and branch webs 26 which extend from the web 25 to the corners 27 of the ring. Thus the webs 26 extend obliquely to the axis of the projection and provide an inclined guideway against which the nose of the projection on a coacting head may engage during the coupling operation. By utilizing a plurality of spaced guideways, the possibility of the head being jammed into any of the openings is minimized, as the guideways will deflect the head into proper coupling position. A further advantage of the guideway, which I have illustrated is the fact that it serves as a reinforcement for the ring and also serves to transmit working stresses directly to the head while retaining the advantages of an open ring.

To facilitate withdrawal of the heads to the normal position in case the heads should pass each other on the ring side, I have shown the rear edges of the arms 26 as extending to the extreme marginal edges of the ring. I have also shown the ring as having webs 30, which extend horizontally at spaced intervals along the back part of the vertical portion of the ring. These webs provide an inclined surface and thus avoid the possibil-

ity of one ring binding behind another in case the connectors slide past each other, during the coupling operation on extreme conditions of track curvature.

5 I claim:

6 1. An automatic train pipe connector head, having a projection and ring disposed on opposite sides of the connector axis, and a web-like inclined guideway disposed between the 10 top and bottom walls of the ring opening and extending from the outer wall of the ring to the head.

15 2. In an automatic train pipe connector, the combination with a connector head having a projection and a ring disposed on opposite sides of the midportion of the connector, of a web extending from the head and across substantially the midportion of the ring to the outer wall of the ring, said web being 20 inclined to the meeting face of the connector and cooperating with the projection of a coacting head to guide it into proper coupling position.

25 3. An automatic train pipe connector head having, in combination, a projection, a ring and a narrow strut having a portion thereof extending across the midportion of the ring opening and providing a guideway for the projection of a coacting head.

30 4. In an automatic train pipe connector, the combination with a connector head having a projection and a ring disposed on opposite sides of the midportion of the head, there being spaced arms extending across the ring 35 opening, and obliquely to the plane of the meeting face of the head, said arms cooperating with the ring, to provide a funnel for guiding a coacting head into proper coupling position.

40 5. In an automatic train pipe connector, the combination of a connector having a projection and a ring, disposed on opposite sides of the midportion thereof, and ribs associated with the ring and extending diagonally 45 from the head and across the ring opening between the top and bottom walls thereof, said ribs cooperating with the ring to guide the projection of a coacting head into proper coupling position.

50 6. An automatic train pipe connector head having in combination, a projection and a ring disposed on opposite sides of the midportion thereof, a ribbed web extending laterally of the head and adjacent the axis thereof, and means connecting the web to spaced points on the ring.

55 7. An automatic train pipe connector head, having in combination, a projection and a ring, adapted to cooperate with a corresponding ring and projection on a mating head, there being arms extending across the ring opening and converging to a point located in a plane rearwardly of the ring, said arms 60 cooperating with the ring to form a funnel.

and to guide a projection on a mating head during the coupling operation.

8. An automatic train pipe connector head having in combination, a projection and a ring disposed on opposite sides of the midportion thereof, said ring having top, bottom, inner and outer side walls, the outer side wall having spaced inclined webs on the rearward portion thereof for enabling one head to be disengaged from a coacting head in the event that the heads should be moved past each other during the coupling operation.

9. In testimony whereof, I hereunto affix my signature.
